[57] **ABSTRACT**

A single guide-bar, warp-knit crepe fabric is provided. The fabric has a repeating stitch pattern that includes at

least two stitches selected from the group consisting of a three-needle open stitch, a two-needle open stitch and a one-needle open or closed stitch. The floats of the repeat pattern are no longer than four-needle spacings. Four-course repeating patterns are preferred, especially one having a 0-2, 2-3, 4-2, 2-1 repeat.
